UNITED STATES PATENT OFFICE.

JOHN H. KING, OF CINCINNATI, OHIO.

METHOD OF MOLDING STICKY AND VISCOSUS MATERIALS.

1,165,677.

Specification of Letters Patent. Patented Dec. 28, 1915.

Application filed July 20, 1914. Serial No. 851,838.

To all whom it may concern:

Be it known that I, JOHN H. KING, a citizen of the United States, and a resident of the city of Cincinnati, in the county of 5 Hamilton and State of Ohio, have invented certain new and useful Improvements in the Methods of Molding Sticky and Viscous Materials, of which the following is a full, clear, and exact description, reference being 10 had to the accompanying drawings, forming part of this specification.

It has been found that in handling materials such as semi-liquid paper pulp, chemically treated with a quick drier and hardener, which makes a very viscous and sticky mass, that all known methods of molding it result in a hopeless clogging up of parts, rendering pouring and pressing so difficult and expensive as to be impractical for general use. The material such as above mentioned may be handled either hot or cold, but it hardens very quickly, and it will stick to the male and female parts of a die before anything can be done with it. It will not 25 pour properly, nor can it be drawn from the heating engine by suction, as in the ordinary atomizer.

The object of the invention here is hence to convey, mechanically, from a source of 30 semi-liquid, the material to be used, and to atomize the same and spray it over the surface of a former, whatever its shape, where it adheres by impact.

This method of treatment is described in 35 detail with reference to a preferred embodiment in the machine illustrated in the drawings, and the novelty therein duly claimed.

In the drawings, Figure 1 is a central vertical section of the machine. Fig. 2 is a detail vertical section showing the conveyer and a stuffing box. Fig. 3 is a plan view of 40 the mounting means of the conveyer. Fig. 4 is a side elevation of the whole machine on a small scale.

45 Industrially the principal application of this invention as designed is for the manipulation of paper pulp in connection with various chemical ingredients in order to render said material hard and water-resisting,

but it is not desired to be limited to the use 50 of the machine or device to the above material, as pitch, resin, glue or in fact any semi-liquid, or viscous material may be worked with equal facility.

The mechanical part of the invention consists of a reservoir or "cooker" 1, having a steam jacket 2 in the lower half of said receptacle for the purpose of admitting steam of varying temperature into the jacket, for the purpose of maintaining the contents of 55 60 said kettle or reservoir in a liquid or semi-liquid state to admit of same being conveyed vertically by means of a spiral conveyer 3. This conveyer works in a hollow cylinder 4, by means of a rod or shaft 5 extending 65 through the bottom of the steam jacket 2, and then revolved by means of a motor or other driving device, situated on the exterior of the kettle through the gears 6, 6. The rod or shaft in passing through the bottom 70 of the steam jacket, is provided with stuffing boxes 7, 7, packed with suitable metallic or other packing 8. The material in the kettle or reservoir is carried upward by the operation of the spiral conveyer and 75 issuing from the upper extremity of the containing cylinder is met by a jet of compressed air or gases, the same being either cold, or heated. The jet issuing from the nozzle may also be of superheated steam, if 80 the material used be of such nature as to require it.

The use of a spiral conveyer is of considerable importance, as with such conveyer the material delivered to the jet may be 85 maintained in a homogeneous condition, free from lumps, and the delivery of the material can be regulated and the material distributed for the uniform and proper action of the spraying device. With such material 90 as paper pulp, a uniform, even delivery to the jet is very essential, and for this sort of material a spiral conveyer is of great value.

The jet nozzle 9, located at the top and slightly in the rear of a small cylinder at the 95 upper end of the conveyer, containing the material to be used, is directed in such manner as to atomize and drive the contents for-

ward and against any plane or irregular surface, depositing the same in regular and equal amounts thereon.

It is not thought that further drawings 5 are necessary to illustrate the modifications of my device which suggest themselves.

The device may be operated either singly or in multiple; the jets may force the contents of the cylinder directly forward, or if 10 in multiple the lines of atomized material may cross each other at an angle, so as to produce an interlacing of the material (if same is composed of paper pulp). If certain effects have to be produced in the mate-

15 rial, liquid or gaseous chemical substances may be introduced into the jets as they carry the air or gases forward. As a means of doing this, an auxiliary inlet 21 is provided for the pipe 9^a leading to the atomizing

20 nozzle 9. It is further advisable not to allow the leakage from the conveyer to drop back into the heated mass. For this reason, the end of the cylinder 4 overhangs the kettle 1, and a pan 22 is provided to catch the 25 drippings which can be used again. The tube or cylinder extending through the bottom of the kettle is slotted longitudinally for a portion of its length at 11, to provide opening for the material to be conveyed up-

30 ward and outward by the screw conveyer. The stuffing boxes and glands are designed to form a guide for the lower extremity of the screw conveyer, the tube or cylinder itself forming a guide or support above.

35 This tube is preferably attached rigidly to the body of the kettle 1 by means of the brackets 12 and 13, the lower of which has a slot 14 to coincide with the slot 11 above noted.

40 The mold or former is the article that is moved to receive the desired form of coating for the finished product. As the material of a kind such as this is sprayed or atomized, it sticks to the impeding surface. Unlike the ordinary spraying, it is 45 is the mold that is moved and not the nozzle. Slight movement of the nozzle in the machine shown would be possible, but means of moving the mold is usually the only practical way of spreading the material. If it is desired to regulate the spraying force, the nozzle may be drawn back by the rack and pinion 15, 16, secured to the nozzle pipe 9^a. In the former shown, for example, the

50 shape is that of a keg. This keg former 17 is collapsible being built along the same lines as my collapsible cylinder shown and described in Letters Patent in my name, No. 716,555, and dated December 23, 1902, and

55 it is covered with material coated so that the dried material will not stick to it. The former 17 is mounted in trunnions 18, movable on a track 19, and is revolved by a handle 20. It will be understood that in

making flat board, beaded strips, and such 65 like, that the movement of the former will be different. It will also be understood that while I have illustrated a receptacle with steam jacket for heating, that in many instances the semi-liquid plastic materials 70 can be treated without heating.

What I have sought to disclose as far as mechanism is concerned is an apparatus or device for mechanically conveying through 75 a tube or conduit, paper pulp or other semi-plastic or viscous material, which is met at its upper extremity by a jet of compressed air and sprayed or projected against a form or pattern of either plane or irregular outlines. In addition to paper material, semi- 80 liquid glue, casein, varnishes, or such matter can also be treated, which will not flow by gravity through an orifice in a regular and uniform quantity. Through the inlet in the air pipe, formaldehyde or other 85 chemical substances when desired, may be utilized for hardening, or giving other properties to the substance being used.

Having thus described my invention, what I claim as new and desire to secure by Letters Patent, is:—

1. A method of molding sticky and viscous and rapidly hardening materials such as chemically treated paper stock, which 95 consists in mechanically conveying in an upward direction the mixture from a source subjected to heat, whereby none of the material is allowed to drip away by gravity, and at the topmost point to which it is conveyed directing a powerful jet of air against 100 the material, so as to atomize it and project it directly against a mold or former.

2. A method of molding sticky and viscous and rapidly hardening materials such as chemically treated paper stock, which 105 consists in continuously and mechanically conveying in an upward direction the mixture from a source subjected to heat, whereby none of the material is allowed to drip away by gravity, and at the topmost point 110 to which it is conveyed continuously directing a powerful jet of air against the material, so as to atomize it and project it directly against a mold or former.

3. A method of molding sticky, viscous 115 and rapidly hardening materials such as chemically treated paper stock, which consists in maintaining the source of supply thereof in a vessel subjected to heat, mechanically and upwardly conveying said material from said source to a point substantially horizontal to the mold or former, and at said point directing a powerful jet of air against the material so as to atomize it and project it directly against the mold or 120 former.

4. A method of molding sticky, viscous and rapidly hardening materials such as

chemically treated paper stock, which consists in maintaining the source of supply thereof in a vessel subjected to heat, mechanically and upwardly conveying said material from said source to a point beyond the edge of the vessel and substantially horizontal to the mold or former, and at said point directing a powerful jet of air

against the material so as to atomize it and project it directly against the mold or former.

JOHN H. KING.
